US0D1044759S

(12) **United States Design Patent** (10) Patent No.: **US D1,044,759 S**
(45) Date of Patent: ** Oct. 1, 2024

(54) **SUPPORT FOR SCANNER**

(71) Applicant: **SHINING 3D TECH CO., LTD.**,
Hangzhou (CN)

(72) Inventors: **Haimin Zheng**, Zhejiang (CN); **Chao Ma**, Zhejiang (CN); **Xiaobo Zhao**, Zhejiang (CN); **Xiaojun Chen**, Zhejiang (CN)

(**) Term: **15 Years**

(21) Appl. No.: **35/517,573**

(22) Filed: **May 4, 2023**

(80) **Hague Agreement Data**

Int. Filing Date: **May 4, 2023**

Int. Reg. No.: **DM/229556**

Int. Reg. Date: **May 4, 2023**

Int. Reg. Pub. Date: **Jun. 23, 2023**

(30) **Foreign Application Priority Data**

Nov. 4, 2022 (CN) 202230737227.X
